M. SCHMIDT

SCALPEL

Filed Nov. 10, 1924

INVENTOR

Max Schmidt.

BY James N. Ramsey

ATTORNEY

UNITED STATES PATENT OFFICE.

MAX SCHMIDT, OF CINCINNATI, OHIO.

SCALPEL.

Application filed November 10, 1924. Serial No. 748,810.

My invention relates to scalpels for anatomical surgical operations or dissections.

The objects of my invention are to provide an extremely simple, efficient and practical 5 scalpel handle, and interchangeable blades therefor of various sizes and styles for particular uses, which are adapted to be easily, conveniently and securely, detachably and interchangeably secured to the handle without 10 any separate or extraneous fastening means; to provide a handle in which one of the blades may be concealed therein to prevent unintentional cutting or injury therefrom and to protect the cutting edge against 15 damage; to provide means whereby the blade is secured in position without weakening it to render it liable to breakage and particularly while performing an operation; to provide means whereby the shank and a portion 20 of the back of the blade are reenforced to insure absolute safety in its use; to provide simple and secure blade holding means; to provide convenient and easily operated blade attaching and detaching holding means 25 without danger of cutting the fingers; to provide means whereby great economy and convenience is effected in requiring only a single handle adapted to be interchangeably used with a multiplicity and variety of blades and 30 whereby the handle and blades may be conveniently carried or stored in a very compact space; and to provide a peculiar form of handle adapted to be dependably, securely and firmly grasped by the surgeon or 35 operator when performing an operation or when dissecting.

My invention consists in the peculiar construction, combination, location and arrangement of parts as herein set forth and claimed.

40 In the drawing:

Fig. 1 is a side elevation of the handle showing the blade represented by dotted lines in closed or concealed position;

Fig. 2 is a longitudinal edge view with 45 the blade in concealed or closed position;

Fig. 3 is an inside elevation of one side of the handle;

Fig. 4 is an inside elevation of the other side of the handle showing the position of the 50 blade relative thereto;

Fig. 5 is a side view of one of the blades;

Fig. 5^a is a side view of a different form of blade;

Fig. 6 is a longitudinal edge elevation of 55 the part of the handle shown in Fig. 4 with the blade omitted;

Fig. 7 is a view of the handle and blade in one position while being assembled or disassembled;

Fig. 8 is a perspective view of the scalpel 60 with still another form of blade in position for use; and

Fig. 9 is a longitudinal edge view showing the normally overlapping position of the end portions of the handle plates when assembling or disassembling the parts and when 65 not in parallel assembled relation.

In the preferred construction of my invention I provide handle or holder 1 consisting of longitudinal plates 2 and 3 formed so 70 that when they are positioned upon each other in their proper relation, as shown in Fig. 1, the complete outer edge of one plate registers with the complete outer edge of the other plate. Plate 2 has spaced apart 75 curved grooves 4 and 5 disposed transversely thereof in its inner side 6 and positioned intermediate the front and rear ends 7 and 8, respectively, and adjacent the front end for the purpose of providing clearance for 80 the ends of studs 14 and 15 on plate 3 when the plates and blade are being assembled and to permit them to ride up out of said grooves into firm engagement with the inner surface of the opposite plate. Plate 2 85 also has key hole 9 therethrough and disposed intermediate curved grooves 4 and 5 for the purpose of receiving head 10 of key pivot 11 secured to inner side 12 of plate 3 and extending outwardly therefrom adjacent end 13 for the purpose of retaining 90 plates 2 and 3 in registering engagement with each other. Spaced apart studs 14 and 15 disposed on opposite sides of pivot 11 and in alignment therewith are fixed to or 95 integral with inner side 12 of plate 3 and extending outwardly therefrom to engage spaced apart perforations 16 and 17 in scalpel blade 18, pivot 11 being inserted through hole 19 for the purpose of locking the blade 100 between plates 2 and 3. Plates 2 and 3 each have centrally disposed outwardly curved or offset portions 20 and 21 whereby the rear portions 22 and 23 of the plates are spaced apart a considerably greater distance 105 than the front portions thereof when the plates are in assembled position, as shown in Fig. 2. The rear portions 22 and 23, respectively, of plates 2 and 3 converge inwardly from the curved portions toward the extreme ends 8 and 24, respectively, whereby said plates are adapted to be sprung into

firm clamping contact with the blade and with each other, thereby permitting stud 25 (adjacent end 24 and fixed to or integral with inner side 12 of plate 3) to engage perforation 26 in end 8 of plate 2 whereby holding spring tension is produced in the plates by the metal or other material from which they are made, and which tension maintains ends 8 and 24 in engagement with each other thereby retaining stud 25 in perforation 26 whereby the blades are securely held in fixed relation to each other. The longitudinal back 27 of blade 18 is securely retained in fixed alined relation with edge 28 of handle 1 by studs 14 and 15 of plate 3, respectively engaging perforations 16 and 17 in the blade which is maintained rigidly against lateral or bending movement by extended ends 29 and 30, respectively, of plates 2 and 3 engaging the back portion of the blade substantially as shown.

For the purpose of providing dependable means to enable an operator or surgeon to firmly grasp handle 1 outer sides 32 and 33 of plates 2 and 3 are provided with knurled, milled or transversely grooved surfaces 34 and 35, respectively, which tend to prevent accidental or unintentional slipping of the scalpel in the fingers of surgeons when performing delicate operations. Said transversely grooved surfaces are also provided to permit the plates to yield apart under manual pressure to permit the ends of the plates to be sprung past each other from the position shown in Fig. 9 to pass over stud 25 in assembling or disassembling the parts.

To mount the blade in the handle ready for use place the blade 18 with its back 21 in alinement with edge 28 of plate 3 permitting stud 14, pivot 11 and stud 15 on plate 3 to enter perforation 16, hole 19 and perforation 17, respectively, in the blade. Head 10 on the outer end of key pivot 11 is then inserted through enlarged portion 36 of key hole 9 so that the inner side of plate 2 engages blade 18. Pivot 11 is then slid into smaller portion 37 of key hole 9 which operation is most conveniently accomplished when the plates are substantially at right angles to each other, as shown in Fig. 7. End 8 of plate 2 is then rotated on said pivot into engagement with end 24 of plate 3 and the ends (which normally converge past each other transversely at their ends) are then manually sprung or forced apart over stud 25 whereby it is permitted to enter perforation 26 whereupon the assembled handle and blade appear as shown in Fig. 8 in which position the handle and blade are maintained in firm holding relation to each other ready for use by the surgeon or other operator.

When it is desired to carry the scalpel in the pocket blade 18 may be placed in closed position relative to handle 1 by placing end

81 thereof between plates 2 and 3 for inserting studs 14 and 15 of plate 3 into perforations 17 and 16, respectively, after which plate 2 may be mounted in position thereon in the manner above described. 70

When it is desired to remove the blade either when in operative position or when in concealed position between the plates 2 and 3 insert the thumb nails in the space between the plates pressing outwardly until 75 stud 25 is released from perforation 26 then move plate 2 upon pivot 11 until it is in substantially the position as shown in Fig. 7, then push the plate toward the pivot until the head 10 thereof is in registry with the 80 enlarged portion 36 of key hole 9 as shown in said figure whereupon plate 2 may be removed by drawing it away from the blade. The blade can then be readily lifted from its engagement with plate 3. 85

Thus it is seen that I provide a perfectly sanitary device the parts of which are adapted to be readily separated and thoroughly sterilized and cleaned. Very thin blades may be used by reason of the fact that they are reenforced at the back of their attaching end portion and they are not cut away longitudinally adjacent the cutting edge whereby the blade is weakened so as to render it uncertain as to safety from breaking while performing an operation. These thin blades are adapted to be quickly removed from the handle and new blades easily inserted without danger of cutting the fingers. The cost of new blades is about the same as the charge 90 for sharpening the old style knives integral 100 connected to the handle and all of which must be discarded when the blade becomes worn, whereas with my invention the handle may be used indefinitely with new blades 105 thus effecting a great saving in expense. The regular scalpel shape of the device is retained and it is thus possible to have a new knife for every capital or prominent operation. 110

An important advantage of my invention is that various sizes and styles of blades may be detachably and interchangeably secured in the handle whereby the necessity of a large investment of money in the usual assortment of old style knives having the blades and handles integral is eliminated. 115

While I have shown and described a particular construction and arrangement of parts it is to be understood that it is capable of some modification without departing from the scope or spirit thereof as defined in the claims, as for instance the blades and the end of plate 2 may be provided with sockets instead of perforations and where perforations are referred to, either in the specification or claims, it is understood to cover sockets or perforations or both. 120

What I claim as new and desire to secure by Letters Patent is: 125 130

1. In a scalpel, an interchangeable handle adapted to hold blades of various sizes and styles, each of said blades having a hole and perforations through its shank, said handle comprising plates one of which has upon its inner side transversely disposed curved grooves and a key hole having an enlarged end between said grooves and the other of which plates has a key pivot adapted to enter 5 said key hole and having a head adapted to engage the outer surface of the handle adjacent the narrow portion of said key hole, studs on said other plate adapted to extend through the perforations in said blade and 10 traverse said grooves, respectively, and transverse grooves in the outer sides of said plates to form non-slipping holding surfaces and to permit said plates to spring or yield apart under pressure when assembling or 15 disassembling the parts.

2. In a scalpel, an interchangeable handle adapted to hold blades of various sizes and styles, each of said blades having a hole and perforations through its shank, said handle comprising plates one of which has upon its inner side transversely disposed curved grooves and a key hole having an enlarged end between said grooves and the other of which plates has a key pivot adapted to enter 25 said key hole and having a head adapted to engage the outer surface of the handle adjacent the narrow portion of said key hole, and studs on said other plate adapted to extend through the perforations in said blade and 30 traverse said grooves, respectively, while entering them and then riding or moving up out of said grooves into engagement with 35

the inner surface of the opposite plate to hold the parts firmly together transversely.

3. In a scalpel, a blade having a hole and a perforation on each side thereof, a pair of detachable spring metal plates forming a handle for said blade, one of said plates having registering cooperating studs adapted to engage said perforations and one of said plates having a slotted key hole with an enlarged end and the other of said plates having registering cooperating studs adapted to engage said perforations and having a headed key pivot adapted to enter the hole 40 in said blade and the enlarged end of said key hole and to permit the head of said key pivot to be moved over the narrow ends of said key opening whereby when said plates are moved into parallel opposing position 45 said blade will be firmly clamped between said plates, substantially as set forth and for the purposes specified.

4. In a scalpel, a blade having a key opening and a perforation on each side thereof, a pair of plates one of which is provided with an elongated key hole having an enlarged portion and the other of which is provided with studs adapted to enter said perforations and with a key pivot having a head adapted 50 to enter said enlarged end to permit said key pivot to be slid into engagement with the narrow end of said key hole whereby said plates firmly clamp said blade therebetween when moved to parallel position with each other and detachable means for holding the butt ends of said plates in parallelism.

MAX SCHMIDT.
